UNITED STATES PATENT OFFICE.

ABRAHAM H. GOLDEN, OF NEW YORK, N. Y.

BUTTON.

1,297,345.

Specification of Letters Patent. Patented Mar. 18, 1919.

Application filed July 31, 1918. Serial No. 247,515.

To all whom it may concern:

Be it known that I, ABRAHAM H. GOLDEN, a citizen of the United States of America, residing at New York city, county and State 5 of New York, have invented certain new and useful Improvements in Buttons, of which the following is a full, clear, and exact description.

This invention relates to improvements 10 in buttons, one of the objects being to provide a button having a shank for detachable securement to garments, special locking means for the shank being provided.

I will now proceed to describe my invention in detail, the novel features of which, 15 I will point out in the claim, reference being had to the accompanying drawing, forming part hereof, wherein:—

Figure 1 represents an edge view in elevation of my improved button, the hook being in position for attachment to the fabric;

Fig. 2, a vertical cross section, enlarged, 20 through the same in normal or fastening position, the shank and tail being in side elevation and the remainder of the hook broken away; and

Fig. 3 represents in detail a top plan view 25 of the base plate and shank shown in Fig. 2.

A preferably convex cap A and flat base 30 plate B constitute the head of the button, which is attached to the fabric of any garment by a suitable spring pressed device, preferably a pointed hook C, which occupies the inclined position shown in Fig. 1 for 35 more conveniently catching into the fabric, and thereafter is turned pivotally into the position shown by the shank of said hook in Fig. 2, for securely holding said button head to said fabric. The button head is of course 40 passed through any ordinary button-hole of an opposite flap or other part of a garment in the usual way. The shank of said hook has, angularly bent therefrom and preferably at right angles thereto, a rigid tail-piece 45 C', which is provided with lateral trunnions D, having their bearings in recesses b of the base plate B. The trunnions and bearings

permit the pivotal movement aforesaid of the hook.

The middle part of said base plate is 50 struck up to form an elongated spring plate E, integral with the base plate B, but severed therefrom at its sides by narrow slits. When the attaching hook is in its inclined position, for catching into the fabric, this spring plate 55 bears on the edge of said tail piece, holding the hook in such position. When the hook, after entering the fabric, is moved into the holding position, the said spring plate bears on the flat surface of the tail piece, as in 60 Fig. 2. In either case the pressure is great enough to prevent accidental displacement; but a very moderate force applied by hand will turn the hook pivotally from either position to the other.

This button is complete in itself, requiring 65 no separate or separable base socket or other part as is common in studs, collar buttons and the like. Its parts are all permanently held together and it is at all times ready for 70 attachment to a fabric without the assistance of any other device. It may be readily removed by reversing the procedure above stated and drawing the oblique hook out of 75 the fabric.

What I claim as my invention is:

A button-head comprising a cap and a flat plate, the latter having a part struck up to form a spring integral with said plate and being provided with a pair of bearing recesses, in combination with means for attachment to a fabric, said means including a latch having an angularly bent tail piece provided with a pair of trunnions arranged to be mounted pivotally in said recesses, said 85 spring operating to hold said latch in either one of two positions.

Signed at New York city, N. Y., this 30th day of July, 1918.

ABRAHAM H. GOLDEN.

Witnesses:

MAURICE BLOCK,
EDWARD A. JARVIS.
